CONNECTOR

Oscar F. Tallman, St. Louis, Mo., assignor to
 James R. Kearney Corporation, St. Louis, Mo.,
 a corporation of Missouri

Application February 16, 1942, Serial No. 431,109

3 Claims. (Cl. 287—50)

This invention relates generally to connecting devices and more specifically to connectors intended for use in mechanically and electrically connecting together electrical conductors, the predominant object of the invention being to provide a connector of this type which is of extremely simple and inexpensive construction and arrangement and which is capable of performing its intended function in a highly efficient manner.

In the maintenance and operation of electrical power distribution systems, and other electrical systems, it is frequently necessary to connect to feed or energy supply lines of the systems, electrical conductors which serve as tap-off wires, leads, ground wires, etc. Some years ago such connections were made by soldered joints, and subsequently a connector of the split-bolt type came into rather general use for making such connections, this connector comprising a bifurcated bolt which was arranged in straddling relation with respect to the feed line and the conductor to be connected thereto and which had screwthreadedly associated therewith a nut and washer assembly that was screwed into a position relative to the head of the bolt where it clamped the conductor to the feed line.

The prime purpose of this invention is to provide a connector adapted to perform the function referred to above, which is extremely simple in construction when compared with the connectors of the split bolt type heretofore employed for the purpose, and which is capable of easier and more convenient application to conductors to be connected thereby than were said split bolt connectors, said connector, because of its improved construction and arrangement, serving to apply to the conductors connected thereby continuing spring pressure whereby looseness of the connected conductors due to wear thereof is prevented.

Fig. 1 is a plan view of the improved connector showing same as it appears when connecting a secondary conductor to a main conductor.

Fig. 2 is a side elevation of the connector and conductor assembly illustrated in Fig. 1 but with the secondary conductor shown in section.

Fig. 3 is a section taken on line 3—3 of Fig. 2 looking in the direction indicated by the arrows.

Fig. 4 is a section taken on line 4—4 of Fig. 2 looking in the direction indicated by the arrows.

Fig. 5 is a plan view of a modified form of the invention.

Fig. 6 is a side elevation of the assembly illus-

trated in Fig. 5 but with the secondary conductor shown in section.

In the drawing, wherein are shown for the purpose of illustration, merely, two embodiments of the invention, A designates in Figs. 1 to 4, inclusive, one form of the improved connector generally. The connector A is formed from a length of wire, or other suitable material, which is bent double to provide a curved bridge portion 1 at an end of the connector from which are extended opposed, elongated leg portions 2 and 3, the material of which the connector A is formed being characterized by being highly resilient so that the outer, free end portions of the opposed legs 2 tend to spread apart.

The portions of the legs 2 and 3 of the connector A which are located immediately adjacent to the bridge portion 1 provide gripping portions 4 and 4' shaped as shown to the best advantage in Fig. 2, said gripping portions being formed by angular portions 5 and 6 of said legs which extend upwardly and forwardly from the opposite sides of the bridge portion 1, curved seat portions 7 and 8 which are continuations of said angular portions 5 and 6, and downwardly and forwardly extended, angular portions 9 and 10 which join the seat portions 7 and 8 with the forward portions of the leg portions 2 and 3. At the forward end portion of the leg portion 2 of the connector A a curved portion 11 is provided which is extended laterally of the connector at a forwardly projected angle, said laterally extended portion terminating in a short, forwardly projected, straight portion 12. In like manner the leg portion 3 of the connector A is provided at its forward portion with a curved portion 13 which extends laterally of the connector at a forwardly projected angle and in the opposite direction to the direction of projection of the laterally extended portion 11 of the leg portion 2, said laterally extended portion 13 terminating in a short, forwardly projected, straight portion 14. As shown in Figs. 1 and 2 the leg portion 3 is shorter than the leg portion 2 so as to offset the portions 11 and 13 of said legs 2 and 3, longitudinally of the connector A.

When it is desired to employ the improved connector A to mechanically connect a secondary conductor to a main conductor, such as the main conductor M and the secondary conductor S shown in Figs. 1 and 2, a portion of the secondary conductor is arranged at a substantial right angle relative to the main conductor. The connector A with its leg portions 2 and 3 spread

apart is then applied to the main conductor M from beneath same, so that the leg portions of the connector straddle the main conductor and the curved bridge portion 1 of said connector embraces the lower portion of said main conductor. The connector A is then drawn to a position where it is substantially parallel with the main conductor and where the gripping portions 4 and 4' embrace the upper portion of the secondary conductor, in which condition the secondary conductor is securely gripped between the seat portions 7 and 8 of the leg portions of the connector and the top surface of the main conductor M. The curved, laterally extended portion 13 of the leg portion 3 of the connector is then moved beneath the main conductor M where it embraces the lower portion of the main conductor and where the straight portion 14 contacts with an upper, side surface portion of said main conductor, and likewise the curved, laterally extended portion 11 of the leg portion 2 of the connector is moved beneath the main conductor to a position where it embraces the lower portion of said main conductor and where the straight portion 12 contacts with an upper, surface portion of the main conductor at the opposite side of said main conductor from that with which the straight portion 14 of the leg portion 3 contacts.

When the connector A has been applied to an assembled secondary conductor and main conductor as described, the secondary conductor S of the assembly is forced into close contact with the main conductor M thereof and is held in that position to provide secure mechanical attachment and good electrical connection between said conductors. Also because of the resiliency of the elongated leg portions 2 and 3 point-pressure, spring contact is applied to the secondary conductor and the main conductor which is continuing, and as a result of this fact wear at the contacting surfaces of the conductors will not produce a loosening of the connection between the conductors, but instead the continuing spring pressure exerted by the connector will maintain the connected conductors in close contact in spite of such wear. Additionally, the use of the connectors of the type disclosed herein greatly simplifies the task of making connections between conductors, because a connection may be made with a few simple hand operations and entirely without the use of tools of any sort.

In Figs. 5 and 6 a slightly modified form of the invention is illustrated. In accordance with the form of the invention shown in these views the elongated leg portions 2' and 3' of the connector A' have formed therein transversely aligned eyes 7' and 8' through which the secondary conductor S' is extended. The connector A' of Figs. 5 and 6 functions just as does the connector A of Figs. 1 to 4, inclusive, the inner surfaces of top portions of the eyes 7' and 8' contacting with upper surface portions of the secondary conductor S', and said secondary conductor being forced into close contact with the main conductor M' by the resiliency of the conductor A'.

I claim:

1. A connector for electrical conductors comprising a structure formed from a single length of resilient material shaped to provide a curved bridge portion and a pair of opposed elongated leg portions which are extended from said curved bridge portion, curved conductor-engaging portions formed on said elongated leg

portions adjacent to the outer ends thereof and arranged in substantial alinement with said bridge portion when the connector is in its effective conductor-connecting condition, said conductor-engaging portions being inclined at angles extended transversely and longitudinally of the connector, said bridge portion and said conductor-engaging portions of said elongated leg portions being adapted to engage one of a pair of conductors connected by the connector, substantially straight portions extended from said conductor-engaging portions of said elongated leg portions, and conductor-gripping portions comprising curved seats formed on said elongated leg portions and offset from the direction of alinement of said bridge portion and said conductor-engaging portions of said elongated leg portions for engaging the other of a pair of conductors connected by the connector.

2. A connector for electrical conductors comprising a structure formed from a single length of resilient material shaped to provide a curved bridge portion and a pair of opposed elongated leg portions which are extended from said curved bridge portion, curved conductor-engaging portions formed on said elongated leg portions adjacent to the outer ends thereof and arranged in substantial alinement with said bridge portion when the connector is in its effective conductor-connecting condition, said conductor-engaging portions of said elongated leg portions being inclined in opposite directions at angles extended transversely and longitudinally of the connector and said bridge portion and said conductor-engaging portions of said elongated leg portions being adapted to engage one of a pair of conductors connected by the connector, substantially straight portions extended from said conductor-engaging portions of said elongated leg portions, and conductor-gripping portions comprising curved seats formed on said elongated leg portions and offset from the direction of alinement of said bridge portion and said conductor-engaging portions of said elongated leg portions for engaging the other of a pair of conductors connected by the connector.

3. A connector for electrical conductors comprising a structure formed from a single length of resilient material shaped to provide a curved bridge portion and a pair of opposed elongated leg portions which are extended from said curved bridge portion, curved conductor-engaging portions formed on said elongated leg portions adjacent to the outer ends thereof and arranged in substantial alinement with said bridge portion when the connector is in its effective conductor-connecting condition, said conductor-engaging portions of said elongated leg portions being inclined transversely and longitudinally of the connector and extended in opposite directions and said bridge portion and said conductor-engaging portions of said elongated leg portions being adapted to engage one of a pair of conductors connected by the connector, substantially straight portions extended from said conductor-engaging portions of said elongated leg portions longitudinally of the connector, and conductor-gripping portions comprising curved seats formed on said elongated leg portions and offset from the direction of alinement of said bridge portion and said conductor-engaging portions of said elongated leg portions for engaging the other of a pair of conductors connected by the connector.
